SWITCH CONTROLLING ASSEMBLY

Walter T. Knauth, Houston, Tex., assignor to
The Milwhite Co., Inc., Houston, Tex., a corporation

Application January 1, 1945, Serial No. 570,822

2 Claims. (Cl. 200—83)

1

This invention relates to a switch controlling assembly.

An object of the invention is to provide means for hydraulically controlling an electric switch and which is specially adapted for use in connection with lines which conduct fluid containing abrasive or other foreign material; the controlling assembly is of such construction that it will exclude all foreign matter from the operating mechanism and will at the same time withstand exceptionally high pressure.

More specifically a further object of the invention is to provide a switch operating mechanism which includes a plunger and a diaphragm so arranged that the diaphragm will separate the liquid from the essential movable parts of the mechanism and, after the diaphragm has been moved by the liquid pressure the required distance to actuate the plunger to operate the switch, said diaphragm will have a continuous, unyielding support which will withstand the maximum excess pressure to which the diaphragm may be subjected without further movement of the diaphragm and consequently without injury to said diaphragm.

With the above and other objects in view the invention has particular relation to certain novel features of construction, operation and arrangement of parts, an example of which is given in this specification and illustrated in the accompanying drawings, wherein:

Figure 1 shows a sectional view of the assembly as connected to a fluid conducting line.

Figure 2 shows a fragmentary side elevation, partly in section, taken at right angles to the view shown in Figure 1; and

Figure 3 shows a sectional view taken on the line 3—3 of Figure 1.

Referring now more particularly to the drawings wherein like numerals of reference designate similar parts in each of the figures, the numeral 1 designates a casing which is formed of heavy material and is preferably cylindrical in shape. At one end the casing is threaded and is shown connected into a T-connection of a fluid conducting line. The other end of the casing is threaded to receive the cover 2 which is provided with a stuffing box 3 to form a seal around the electric wiring 4.

The casing 1 encloses a strong coil spring 5 and is internally threaded, at its outer end, to receive an adjusting nut 6 which is screwed therein against the outer end of the spring 5.

At its other end the casing is internally counterbored so as to provide an inner counter-

2

bore 7 and an outer counterbore 8, the former of which is of less inside diameter than the latter. The annular shoulders 9 and 10 are thus provided.

5 There is a plunger 11 which extends through the casing and through the nut 6, axially.

Fixed on the plunger and working in the counterbore 7 there is the abutment 12 which supports the spring 5.

Fitted into the counterbore 8 and against the shoulder 10 there is the clamp block 13 through which the plunger also works.

Screwed into the inner end of the counterbore 8 there is a clamp nut 14 and the margin of a flexible diaphragm 15 is clamped, by said nut, against the facing side of the block 13. The adjacent end of the plunger 13 normally projects beyond the block 13 and against the diaphragm.

The numeral 16 designates a conventional electric switch to the posts of which the conductors 4 are connected at one end. The other ends of these conductors are connected to an electric motor which operates the pump which pumps the fluid through the line. This switch is supported in position by the legs 17 which may be secured in any preferred manner to the adjacent end of the casing 1. The switch and its operating mechanism are enclosed by the cap 2.

Screwed into the corresponding end of the casing 1 and upstanding within the cap 2 there is a post 18 which is bifurcated at its upper end to receive one end of the lever 19 which is pinned therein. Pivoted to the other end of the lever 19 there is a link 20 which is also pivoted to the control arm 21 of the switch.

35 The lever 19 has a bore intermediate its ends through which a screw 22 is loosely fitted. This screw is screwed into the upper end of the plunger 11 and has a head thereon. A resilient washer 23 is located between the head of the screw and the lever 19 and a similar washer 24 is located between the lever and the opposing end of said plunger. These washers 23 and 24 form cushions.

45 While the fluid flowing through the line 25 is under normal pressure the parts of the assembly will be in the position shown in Figure 1. The bore 7 is of sufficient depth to allow a limited movement of the plunger 11. While the fluid

50 flowing through the line is under normal pressure the abutment 12 will be in contact with the clamp block 13 and the plunger 11 will project beyond said block to hold the diaphragm 15 extended or spaced away from the block 13. This 55 will be effected as a result of the pressure of the

spring 5. Upon an increase in the pressure of the liquid flowing through the line 25 sufficient to overcome the pressure of the spring 5 the increased pressure will be effective to move the diaphragm 15 and the plunger 11 so as to actuate the lever 19 and link 20 which in turn will operate the control arm 21 and actuate the switch. Thus the increase in pressure and subsequent actuation of the switch will be effective to either start or stop an electric motor or other electric appliance.

The movement of the plunger as a result of the pressure in the line is limited by the shoulder 9 and its movement under the influence of the spring 5 is limited by the clamp block 13.

When the plunger is moved as a result of increased pressure in the line 25 into contact with the shoulder 9 the corresponding end of the plunger will be flush with the face of the clamp block 13 which is adjacent the diaphragm and said end of the plunger and said face of the clamp block will form a smooth but firm backing for the diaphragm so that said diaphragm will not be ruptured or injured by the pressure irrespective of the intensity of said pressure over normal.

The switch controlling assembly herein described has been illustrated as connected to a fluid conducting line but it may be connected into any container or system containing fluid wherein the pressure of the fluid varies.

The drawings and description are illustrative merely while the broad principle of the invention will be defined by the appended claims.

What I claim is:

1. A hydraulically operable switch controlling assembly comprising, a casing adapted to be connected to a container for fluid, an adjusting nut having a threaded connection with the casing at one end, a plunger, one end of which extends axially through said nut, a clamp block countersunk into the other end of the casing through which the other end of the plunger works, the outer end of the plunger extending out beyond the block when the plunger is in one position, an annular abutment on the plunger on the inner side of the clamp block, said casing having an inside annular shoulder spaced from the clamp block which limits the inward movement of said abutment and plunger, said shoulder being spaced from the block a distance such that the outer end of the plunger will be flush with the outer side of the clamp block when the plunger reaches the limit of its inward movement to provide a con-

tinuous smooth diaphragm support, a coil spring in the casing around the plunger and interposed between said nut and abutment, a diaphragm exposed to the fluid, a clamp nut threaded into the casing and clamping the margin of the diaphragm against the outer side of the clamp block, and means for operatively connecting the plunger with the switch.

2. A hydraulically operable switch controlling assembly comprising, a casing adapted to be connected to a container for fluid, a closure connected to one end of the casing, a plunger one end of which extends axially through said closure, a clamp block closing the other end of the casing, a diaphragm exposed to the fluid in the container, a clamp nut threaded into the casing and clamping the margin of the diaphragm against the outer side of the clamp block said clamp block having a central bearing through which the other end of the plunger extends, an annular shoulder within the casing spaced inwardly from the clamp block, an abutment on the plunger between the clamp block and shoulder, a coil spring in the casing around the plunger between said closure and abutment and normally holding the abutment against the clamp block with the corresponding end of the plunger projecting beyond the clamp block, said shoulder being spaced inwardly from the abutment a distance equal to the projection of the plunger beyond the clamp block so that when the plunger moves inwardly until the abutment engages said shoulder the outer end of the plunger will be flush with the outer surface of the clamp block to provide a smooth backing face for the diaphragm, and means for operatively connecting the plunger with the switch.
